F. W. WOLF,
THERMOSTATIC SWITCH UNIT,
APPLICATION FILED NOV. 3, 1916.

1,366,759.

Patented Jan. 25, 1921.

UNITED STATES PATENT OFFICE.

FRED W. WOLF, OF DETROIT, MICHIGAN, ASSIGNOR, BY MESNE ASSIGNMENTS, TO
THE ISKO COMPANY, OF CHICAGO, ILLINOIS, A CORPORATION OF DELAWARE.

THERMOSTATIC-SWITCH UNIT.

1,366,759.

Specification of Letters Patent. Patented Jan. 25, 1921.

Application filed November 3, 1916. Serial No. 128,350.

To all whom it may concern:

Be it known that I, FRED W. WOLF, a citizen of the United States, and resident of Detroit, Wayne county, State of Michigan, have invented certain new and useful Improvements in Thermostatic-Switch Units, of which the following is a specification.

This invention relates to thermostats and switches operated thereby, and particularly to a thermostatic switch unit of novel construction.

One of the objects of the invention is to provide a thermostatic switch unit particularly adapted for use in an electrically operated refrigerator apparatus.

Another object of the invention is to provide a thermostatic switch unit adapted to permit the thermostat to depend into a refrigerated space with the switch located outside and preferably above said space.

Another object of the invention is to provide a pivoted switch that may be so operated by a thermostat that it will fall into quick contact with the terminals.

Another object of the invention is to provide a thermostat adapted to depend from a support through an opening in a refrigerator wall and have abundant clearance in said opening to insure its continued operation.

Another object of the invention is to provide a thermostat of U form, in which the inside curve of the U is rounded to prevent accumulation of ice thereon.

Other objects of the invention will appear from the following description taken with the drawing which forms a part hereof, and in which:

Figure 1 is an elevation of one form of thermostatic switch unit built in accordance with this invention, with electrical connections shown diagrammatically;

Fig. 2 is an elevation looking from the right of Fig. 1;

Fig. 3 is an enlarged sectional view on the line 3-3 of Fig. 1; and

Fig. 4 is a section on the line 4-4 of Fig. 1.

Referring to the drawings, 10 represents a base or support which may be of insulating material, such as wood or fiber, and 11 is a flat bracket secured to and depending from the base. The lower end 12 of the bracket is turned at right angles to the body thereof, and a thermostat bar 13 is rigidly

secured thereto as by bolts 14. This bar is preferably flat as shown, being arranged with its flat sides at right angles to the flat sides of the bracket 11, and is composed of two flat strips or bars of metal of widely different coefficient of expansion, such as zinc and hoop iron, firmly secured together as by soldering.

A second thermostat bar 15 similar in construction to the bar 13 is arranged parallel and adjacent thereto, and a rigid connecting piece 16 of U shape is arranged between the lower adjacent ends of the bars. The piece 16 is firmly connected to the bars as by the bolts 17, and it is preferably formed of a bar of metal of substantially round cross section or at least rounded off inside the U for the purpose of preventing the accumulation of ice or frost between the lower ends of the thermostat bars when the device is used in connection with a refrigerating apparatus.

Firmly secured to the upper free end of the bar 15 as by bolts 18 is a bracket 19 for operating the switch hereinafter described. This bracket is arranged parallel and adjacent to the bracket 11 and it will be seen that the cross section of these two brackets is less than the largest part of the thermostat so that there will be ample clearance around them if the unit is inserted through an opening in a refrigerator or adapted to similar use.

On the upper part of the support 10 are two separated terminals 20 and 21 and a third terminal 22 is arranged intermediate of and below the upper terminals and is in the form of a pivot for a switch 23. Said switch comprises a body 24 and a weighted head 25, being somewhat in the form of a hammer, and it is pivoted near its lower end so that by its own weight it is adapted to fall into contact with either one or the other of the terminals 20, 21. It is shown in Fig. 1 in full lines in contact with the terminal 20 and in dotted lines with the terminal 21.

The thermostat hereinabove described is connected to operate the switch 23 and shift it from one of its contact positions to the other. A switch operating bolt 26 is arranged horizontally in the upper part of the bracket 19 as shown in Figs. 1 and 3. Its head 27 may be made of insulating material and formed as a hook, as shown in Fig. 2.

Fig. 3, the hooked space being somewhat larger than the lower end of the switch 23 which the hook surrounds so that there may be some lost motion in shifting the switch 5 to permit the latter to drop from central or vertical position to one of its contact positions. This head 27 is also formed with a shank 28 arranged parallel with the bolt 26 and extending through a hole in the bracket 19 to retain the head in correct position. A 10 spring 29 surrounds the bolt 26 between its head 27 and the bracket 19 and yieldingly presses the bolt toward the left in Figs. 1 and 3. A thumb nut 30 is arranged on the 15 projecting end of the bolt and combined with the spring affords ready adjustment of the connection between the thermostat and the switch.

A conductor 31 leads from the terminal 22 to a battery 32 and conductors 33 and 34 lead from the battery through solenoids 35 and 36 to the terminals 20 and 21 respectively. Thus, in full lines in Fig. 1, the switch 23 is closing the circuit through the 25 solenoid 35, and if moved to its other contact position the circuit will be closed through the solenoid 36.

Other forms may be used without departing from the scope of the invention.

30 Claims:

1. A thermostatic switch unit comprising a support, a thermostat depending therefrom, a switch mounted on said support, a switch operating bolt on the free end of 35 the thermostat, a spring pressing said bolt in one direction, and an adjustable stop nut for positioning said bolt.

2. A thermostatic switch unit comprising a support, a thermostat depending there-

from, a switch mounted on said support, a switch operating bolt on the free end of the thermostat, an insulating block on said bolt, and means for adjusting said bolt on the thermostat.

3. A thermostatic switch unit comprising 45 a support, a thermostat mounted thereon, two separated terminals on said support, a switch in the form of a hammer pivoted on the support with its head adapted to swing into contact with either of said terminals, 50 the pivot being below the head so that the latter will fall on either side of said pivot into quick contact with one of said terminals, and connections whereby the thermostat moves the switch to center position and permits it to fall against one of said terminals.

4. A thermostat comprising a pair of substantially parallel thermostat bars, and a rigid connecting piece between adjacent ends of said bars and having a rounded surface, for the purpose described.

5. A thermostat comprising a pair of substantially parallel thermostat bars, and a rigid U shaped connecting piece between adjacent ends of said bars and having a rounded 65 inner surface.

6. A thermostat comprising a pair of substantially parallel thermostat bars vertically arranged, and a rigid connecting piece between the lower ends of said bars and having a rounded surface.

7. A thermostat comprising a pair of substantially parallel thermostat bars vertically arranged, and a rigid U shaped connecting piece between the lower ends of said bars 75 and having a rounded surface inside the U.

In testimony whereof I affix my signature.
FRED W. WOLF.
